UNITED STATES PATENT OFFICE.

WILLARD BENNETT MILLER AND EDMUND FRANCIS SHOOK, OF CHICAGO, ILLINOIS.

POWER CONDENSER WASHER.

Application filed April 15, 1925. Serial No. 23,279.

This invention relates to improvements in power condenser washers and one object is to provide a device of this class that will direct a stream of water, under pressure, into the condenser tubes, the water hose being adapted to travel in a circle and all of the tubes in the circumference of such circle being washed consecutively. A further object is to provide a washer than can be used while the condenser is in operation. A still further object is to provide a washer that is very efficient in use, and that will clean all of the tubes in the condenser.

With the foregoing and other objects in view the invention consists in the combination and arrangement of parts to be hereinafter fully described, pointed out in the appended claims and illustrated in the accompanying drawing which forms a part of this application and in which—

Fig. 1 is a view of the washer illustrating its application to a condenser.

Fig. 2 is a fragmentary view of the washer taken on line 2—2 of Fig. 1.

Fig. 3 is a sectional view taken on line 3—3 of Fig. 1.

Fig. 4 is a section taken on line 4—4 of Fig. 1.

Like reference characters denote corresponding parts throughout the several views.

One of the serious disadvantages of the known condenser washers is their inability to direct a stream of water into the condenser tube in the plane of the tube. Water directed into the tubes at an angle loses much of its effectiveness through contact with the tube body and consequent loss of force. The present invention is without this disadvantage. The water delivery nozzle travels in a circle and all of the tubes lying in the circumference of that circle are washed. By automatic means the diameter of this circle is changed after each complete revolution so that another circle of tubes is then washed and in this manner all, or practically all of the tubes are reached and washed automatically. Any tube or tubes that are not reached in this manner may be washed singly with the machine or otherwise.

The reference numeral 1 denotes the tube sheet of a condenser and 2 the tubes. The water box 3 has secured thereto the arm 4 through one end of which the rotary shaft 5 extends that is tapped into the water box

3, said shaft being formed throughout a substantial portion of its length with the bore 6 thus providing water feed means from said water box. Secured to the arm 4 and perforated to receive the shaft 5 is the packing gland 7 which is circular in formation and provided with peripheral teeth 8. Bolted to the outer and solid end of the shaft 5 by the heads 9 is the shaft extension 10 formed with the offset 11 whereby said shaft extension is disposed off center with relation to the shaft 5.

The forward end of the shaft extension 10 is disposed at right angles to the body portion and has bolted thereto one end of the post 12 that carries the bearings 13, 14, 15, the bearing 13 being provided with sprockets 16 and 17, the bearing 15 with a sprocket 18 and the bearing 14 with a sprocket 19. 75 The sprockets 17 and 19 are connected by the sprocket chain 20 and the sprockets 16 and 18 by the sprocket chain 21. Secured to the chain 21 by plates 22 is the nozzle carrier 23 that carries the nozzle 24 that 80 leads from the elbow 25 coupled to the hose 26 that leads into the bore 6 in the shaft 5.

A feed shaft 27 driven by the sprocket 19 is operatively supported in bearings arranged in the post 12 and in a bracket 28 85 carried by and rotating with the shaft 5, said feed shaft being provided at one end with the pinion 29 adapted for intermittent engagement with the teeth 8 of the gland 7 as the shaft 5 and connections rotates. A 90 drive shaft 30 operated from any power source is arranged in bearings in a post 31 carried by the said arm 4, said drive shaft having a worm 32 at one end thereof in mesh with the worm gear 33 of shaft 5. 95

In operation the water under pressure leaves the water box through the bore 6 in shaft 5, through the hose 26, elbow 25 and nozzle 24 and is directed into the tubes 2. The shaft 5 is disposed in the plane of the 100 center of the tube sheet and the nozzle is slowly rotated about the shaft 5 by revolution of the same. The post 12 is rotated off center and the nozzle thus caused to describe a circle about the shaft 5 as a center. As the pinion 29 comes in contact with the teeth 8 of the gland 7 it oscillates or rotates the feed shaft 27 thus causing the chain 21 to raise or lower the nozzle a distance equal to the space between the centers 105 of two successive tubes 2 so that a larger or smaller circle of tubes is washed after each

adjustment of the hose by the feed shaft and connections. The pinion 29 will pass entirely about the gland 7 without rotation until it meshes with the teeth 8 thereof which engagement causes it to rotate.

What is claimed is:—

1. In a power condenser washer, a rotary water-feed shaft, a carrier supported at one end of said shaft and rotatable thereabout, mechanism for varying the distance of said carrier from the axis of rotation of the shaft, mechanism operative on rotation of the shaft for actuating the first mentioned mechanism, and a water hose communicating with said shaft and supported at its discharge end by said carrier.
2. In a power condenser washer, a rotary water-feed shaft, a carrier supported at one end of said shaft and rotatable thereabout in a plane at right angles thereto, mechanism for varying the distance of said carrier from the axis of rotation of the shaft, mechanism operative on rotation of the shaft for actuating the first named mechanism, and a water hose communicating with said shaft and supported at its discharge end by said carrier.
3. In a power condenser washer, a rotary water-feed shaft offset at one end, a post having one end secured to the offset end of said shaft, a carrier operatively supported upon said post, means for adjusting said carrier relative to said shaft, means intermittently operative on rotation of said shaft for driving said adjusting means, and a water hose communicating with said shaft and supported at its discharge end by said carrier.
4. In a power condenser washer, a rotary water-feed shaft offset at one end, a post secured to and movable with the offset end of said shaft, a carrier carried by said post and adjustable relative thereto, means for adjusting said carrier relative to said shaft, means intermittently operative on rotation of said shaft for driving said adjusting means, and a water hose communicating with said shaft and supported at its discharge end by said carrier.
5. In a power condenser washer, a rotary water-feed shaft offset at one end, a post carried at the offset end of said shaft, a carrier operatively disposed upon said post, means for adjusting said carrier relative to said shaft, means intermittently operative

on rotation of said shaft for driving said adjusting means, and a water hose communicating with said shaft and supported at its discharge end by said carrier.

6. In a power washer condenser, a rotary water-feed shaft offset at one end, a post carried at the offset end of said shaft, a carrier arranged upon said post and movable therewith and relative thereto, actuating means for said carrier, a stationary gland associated with said water-feed shaft, teeth formed peripherally of said gland, a feed shaft operatively associated with said actuating means, and a pinion fast upon said shaft for intermittent engagement with said teeth as said water-feed shaft rotates.

7. In a power condenser washer, a rotary water-feed shaft, a carrier supported at one end of said shaft and rotatable thereabout in a plane at right angles thereto, means for adjusting said carrier relative to said shaft, first outwardly from the axis of rotation of the shaft and then inwardly toward that axis, means intermittently operative on rotation of said shaft for driving said adjusting means, and a water hose communicating with said shaft and supported at its discharge end by said carrier.

8. In a power condenser washer, a rotary water-feed shaft, a carrier supported at one end of said shaft and rotatable thereabout in a plane at right angles thereto, means for adjusting said carrier relative to said shaft, first outwardly from the axis of rotation of the shaft and then inwardly toward that axis, means intermittently operative on rotation of said shaft for driving said adjusting means, and a water hose communicating with said shaft and supported at its discharge end by said carrier.

9. In a power condenser washer, a rotary water-feed shaft offset at one end, a carrier at the offset end of said shaft and rotatable thereabout in a plane at right angles thereto, means for adjusting said carrier relative to said shaft, means intermittently operative on rotation of said shaft for driving said adjusting means, and a water hose communicating with said shaft and supported at its discharge end by said carrier.

In testimony that we claim the foregoing as our own we have hereto affixed our signatures.

WILLARD BENNETT MILLER.
EDMUND FRANCIS SHOOK.
